DESIGN FOR A SUPPORT FOR A SADIRON

Michael A. Rollman, Landisville, Pa.

Application October 8, 1947, Serial No. 141,803

Term of patent 14 years

(Cl. D49—6)

To all whom it may concern:

Be it known that I, Michael A. Rollman, a citizen of the United States, residing at Landisville, in the county of Lancaster and State of Pennsylvania, have invented a new, original, and ornamental Design for a Support for a Sadiron, of which the following is a specification, reference being had to the accompanying drawing, forming part thereof.

In the drawing:

Fig. 1 is a perspective view of a support for a sadiron, embodying my new design.

Fig. 2 is a side elevational view thereof.

I claim:

The ornamental design for a support for a sadiron, as shown and described.

MICHAEL A. ROLLMAN.
